ELECTRONIC ORGAN

Albert M. Skellett, Madison, N. J., assignor to
National Union Radio Corporation, Orange,
N. J., a corporation of Delaware

Application June 9, 1949, Serial No. 97,953

14 Claims. (Cl. 84—1.21)

1

This invention relates to keyboard-controlled instruments, and more especially to organs for producing tones synthetically by electronic action. Various forms of electronic organs have heretofore been proposed employing electronic tubes as the tone sources. However, in the main, such organs have been very costly to manufacture, assemble and repair, primarily because of the great number of electronic tubes necessary to generate the various tones, harmonics, and tonal combinations. The present invention has, for one of its principal objects, the provision of an electronic organ which is economical to manufacture, and requires a minimum number of electronic tubes to achieve the full complement of organ tones.

A feature of the invention relates to an electric organ employing electronic tubes whose total number is small in comparison with the total number of individual organ tones and harmonic mixtures to be produced.

Another feature relates to an electric organ having a series of multi-section electronic tubes for producing a large series of individual organ tones and various harmonic combinations therewith.

Another feature relates to an electric organ employing a relatively small number of multi-section electronic tubes in conjunction with respective audio frequency oscillatory circuits, one for each tube section, to produce respective fundamental tones.

Another feature relates to an electric organ employing a series of multi-section electronic tubes, each section having a common cathode with individual output anodes and a plurality of intervening electrodes with associated audio frequency oscillatory circuits to generate the various fundamental organ tones, and wherein the various harmonics are obtained by derivation from one of the said intervening electrodes.

A further feature relates to the novel organization of electron tubes and associated oscillatory circuits for producing a series of fundamental tones and harmonic mixtures therewith.

Other features and advantages not particularly enumerated, will be apparent after a consideration of the following detailed descriptions and the appended claims.

In the drawing,

Fig. 1 is a composite schematic structural and wiring diagram of an electronic organ according to the invention.

Figs. 2, 3 and 4 are respective modifications of Fig. 1.

2

Referring to Fig. 1, the numeral 1 represents an electronic tube structure of the type disclosed in my prior Patent No. 2,433,403 and in the Proceedings of the Institute of Radio Engineers, Vol. 36, No. 11, pages 1354-1357. This tube comprises an evacuated enclosing glass envelope 2, having centrally mounted therein an electron-emitting cathode 3. This cathode is preferably of the indirectly heated type comprising a tubular metal sleeve, the external surface of which is coated with electron-emissive material. Insulatingly mounted within the sleeve 3 is a heater element 3a for raising the cathode to its electron emission temperature. Concentrically surrounding the cathode 3 is a cylindrical metal cage consisting of alternate slats 4 and intervening windows 5. Concentrically surrounding the cathode 3 and in alignment with each of the respective windows 5, is a series of foraminous electrodes or grids 6. Likewise, concentrically surrounding the cathode, and in alignment with the grids 6, are the individual output anodes 7. The cathode 3 may be directly grounded, for example by the conductor 8, and the cage of which the shield slats 4 are constituted can be connected by a conductor 9 to a suitable tap 10 on the usual direct current power supply. In accordance with one phase of the invention, this latter circuit includes a series resistor 11, for example of approximately 10,000 ohms for purposes to be described.

In accordance with the invention, each set of electrodes 4, 6 and 7, cooperates with the common cathode 3 to generate a respective sustained electrical oscillation of predetermined respective fixed frequency. Thus, each of these individual sections is connected to attuned oscillatory circuits to generate its respective tonal frequency, the production of which can be controlled by a corresponding key, for example key 12 of the usual organ keyboard. Each of these keys is associated with an individual movable contact 13 and a co-operating common contact strip 14 which is connected to a suitable high potential tap 15 on the direct current power supply source 16. The movable contact associated with each key, for example the contact 13, is connected by conductor 17 to the electrical midpoint 18 on the primary winding 19 of an audio frequency transformer 20. One terminal of the primary winding, for example terminal 21, is connected directly to the associated anode 7, and the opposite terminal 22 is connected through a direct current blocking condenser 23 to the corresponding grid 6. Each grid 6 is connected to a respective grid-leak resistor 24 to the common multiplying conductor

25 which can be returned to ground through a suitable normally-closed switch 26. The winding 19 is shunted by a condenser 27 to form there-with a tuned oscillatory circuit. It will be understood, of course, that each set of electrodes of tube 1 has a similar audio frequency transformer and tuning condenser connected to its respective anode and grid, and each of these circuits is tuned to a different fundamental frequency corresponding to the fundamental tones to be produced. When the various electrodes are energized by suitable potentials as above mentioned, a portion of the primary winding 19 is connected between the grid and cathode of the corresponding tube section, and the remaining portion of this primary winding is connected between the anode and cathode of the same section. Thus, by well-known regenerative feedback principles, each section generates a corresponding audio frequency electric wave. All the secondary windings 28 of the audio frequency transformers are connected in series across the output conductors 29, 30, which are connected to a suitable audio frequency amplifier 31, and thence to a suitable loudspeaker or reproducer 32.

With the foregoing described arrangement, it is possible to produce an individual tone, or simultaneously a series of pure fundamental sustained tones, representing chords. I have found that it is possible to combine with these fundamental frequencies any desired harmonics, by tapping-off from the slat electrodes 4 at the common point 33 through a direct current blocking condenser 33a, a series of filters 34, 35, 36, each of which can be designed to pass a selected harmonic or group of harmonics of the fundamental frequencies appearing at conductors 29, 30. These filters can be controlled by respective stops 37 to determine the desired selection of harmonics to be mixed with the fundamental tones applied to the input of amplifier 31. For this purpose, each of the filters 34, 35, 36, is connected to an individual movable contact 38 controlled by a respective stop 37, and co-operating with a common contact strip 39 which is connected to the input terminals of a suitable mixer network 40. The output terminals of the mixer 40 are then applied to the amplifier 31, thus producing in the loudspeaker any desired fundamental and harmonic content.

In the event that a tremolo effect is to be imparted to the various notes or chords, there is provided a tremolo mechanism consisting of a crank wheel 41 which is connected through suitable gears 42 to a motor 43 so as to drive the wheel 41 at a predetermined rate, for example seven revolutions per second. The eccentric or crank arm 44 of the wheel is connected to a rotatable arm 45 which is adapted to ride over a potentiometer resistor 46. Bridged across the resistor 46 is a suitable source of direct current potential 47, the positive terminal of which is grounded. The arm 45 is also connected to a contact 48 of a tremolo switch 49, the armature 50 of which is connected to conductor 25. The other contact 51 of switch 49 is connected to the negative terminal of a suitable direct current source 52. When the tremolo effect is desired, the arm 45 is moved to engagement with contact 48. Since the arm 45 is continuously moving back and forth across the resistor 46 at a rate determined by the wheel 41, there is thus supplied to the conductor 25 a trembling or varying negative bias which is thus applied to all the grids 6. When the tremolo

effect is not desired, armature 50 is moved to engage contact 51, thus applying a fixed negative bias to all the grids.

It will be clear from the foregoing description that when all the keys of the keyboard are in non-operated condition, none of the tube sections produces tonal oscillations. However, upon pressing a key of the keyboard, the corresponding tone is produced in the loudspeaker 32, since there is immediately applied a plate potential, for example 150 volts, to the corresponding anode 7. This produces a somewhat percussive organ tone or sharp attack. If it is desired to slow-down the attack on the immediate generation of the tone, so as to smooth its percussive effect, a separate normally-closed tonal attack key or stop 43 can be opened to connect in series with the keys, a suitable time-constant circuit constituted of resistor 44 and shunt condenser 45. With the described arrangement, by tapping-off the filters 34, 35, 36, from the slat electrodes 4, the voltage drops developed across resistor 11 by the operation of any of the stops 37, may be used as a source of harmonics which can be mixed with the fundamental tones of the respective individual keys 12 to produce the various kinds of organ tones, such as diapason, flute, oboe, vox humana, etc.

While the drawing shows a tube 1 consisting of twelve individual tone-producing sections, it has been found possible to manufacture tubes of this type with thirty such sections. Since a two-manual organ contains about one hundred and thirty-two keys with twenty-five or thirty-two extra tones for the foot pedals, it is possible, according to the invention, to produce a complete two-manual organ employing only five or six tubes such as tube 1.

In some cases it may be desirable to segregate the various harmonics produced at the several slat electrodes 4. In the arrangement of Fig. 1, all the slat electrodes are interconnected to form a single electrical cage. However, instead of using a single cage, the various slats 4 can be insulated from each other and provided with separate lead-in conductors, and through their respective resistors 11, thus rendering it possible to segregate the various harmonics as may be desired. Such an arrangement is schematically illustrated in Fig. 2 of the drawing. Merely for simplicity of showing, Fig. 2 illustrates only two of the several sections of the tube 1, and the parts of the two figures which are identical in function, are designated alike.

It will be observed that in Fig. 2, instead of employing a single harmonic voltage developing resistor 11 for all the slat electrodes, each slat electrode 4 is connected to the positive terminal 10 through an individual resistor 11a, 11b, etc. These resistors are connected to the respective filters 34, 35, etc., which in turn are connected to the harmonic stop selector 53, and thence through the mixer 40 and the amplifier 31, as above described in connection with Fig. 1, it being understood, of course, that the amplifier 31 is also supplied with the fundamental note frequencies over the conductors 29, 30, as above described. One of the additional advantages for the arrangement of Fig. 2, is that when using a single harmonic voltage developing resistor 11, as in Fig. 1, it may be impractical to provide each of the filters with the proper range and characteristics for all of the frequencies generated in the tube. For example, suppose that the lowest note generated by the tube were middle C (250 cycles per

second), and that the highest was four times that frequency (1024 cycles per second), it would be difficult to design a single filter which would pass, for example, the third, fifth and ninth harmonic of each of these tones, and yet at the same time exclude all other harmonics of the tones. By means of the arrangement of Fig. 2, it is possible to design the proper filter for each note and in fact it is possible to use the same filter for a group of notes which are adjacent in frequency, for example those corresponding to adjacent slats or oscillator sections in the tube 1. If desired, an additional set or sets of filters, for example filters 34a, 34b, 34c can be connected with their inputs in parallel with the inputs to filters 34, 35, 36, etc., and the outputs of these filters 34a, 34b, etc., can be connected together and thence through another harmonic selector stop 54 to the input of mixer 40. This would enable the selection of an entirely different group of harmonics for each note that is generated.

If desired, in order to reduce the likelihood of interaction between the several sections of the tube 1, each of the slats 4 can be provided with an integral radially-extending vane 55 which extends between the anodes and grids of two adjacent sections, to electrostatically isolate them from each other as described in said I. R. E. Proceedings. It will be understood, of course, that the tube structures of Figs. 1 and 2 of the present invention, while substantially the same as that disclosed in the said "I. R. E. Proceedings," do not rely for their operation on the production of a focussed electron beam. In other words, the electrons from the cathode 3 are emitted simultaneously in all directions radially considered around the cathode, and the electrons are not subjected to any rotating fields. In other words, all the anodes 7 are uniformly subjected simultaneously to the electron stream from the cathode 3.

Referring to Fig. 3, there is shown another modification wherein the parts which are identical with those of Fig. 1 bear the same designation numerals. In this embodiment, the tube 1 may be similar in construction to the corresponding tube of Fig. 1. However, each of the output anodes 1 has its surface which faces the cathode 3, provided with a coating of material which emits secondary electrons when bombarded by the primary electrons from the cathode 3. Each anode 7 has connected thereto a tuned oscillatory circuit comprising the low frequency inductance coil 20 and the parallel tuning condenser 27, each such combination being tuned to a separate fundamental frequency. The tuned circuits are connected to a common return conductor 56 and thence through the primary winding 51 of an output coupling transformer to an adjustable tap 58 on the direct current plate power supply 16. Each of the control grids 6 is connected through a corresponding individual conductor 17 to the movable contact 13 of a corresponding organ key 12. The common contact 14 for all the organ keys is connected through the attack control key 43 to the terminal 15 on the power supply 16. It will be observed therefore, that the grids are at a higher positive potential than each of their associated anodes so that in conjunction with their respective tuned circuits they provide a series of individual dynatron oscillators. These dynatron oscillators can be selectively rendered effective to generate the respective tones in accordance with the particular organ key that is operated. In order to select the harmonic content, the slat electrodes 4 are

connected to a common conductor 9 and thence through a suitable resistor 11 to the common point 10 which is coupled through the condenser 33a to the respective harmonic stops 37 as above described. These stops are then coupled through the mixer 40 and the audio frequency amplifier 31 to the loudspeaker 32. The fundamental tones are coupled by the secondary 59 of the audio frequency coupling transformer via conductors 10 29 and 30 to amplifier 31 as above described.

Fig. 4 shows a modification of Fig. 3, wherein the parts which are identical with those of Fig. 3 and of Fig. 1 are designated by the same numerals. In the embodiment of Fig. 4, the grids 6 are deleted and the slat electrodes 4 in addition to acting as windows for the electrons, also act as the secondary electron collectors. The anodes 7 are connected through respective individual tuned oscillatory circuits 27, 20, to the common conductor 56, which is connected through resistor 11 to a tap 58 on the direct current plate power supply 16. Each of the slat electrodes 4 is connected through its individual conductor 17 to the corresponding organ key contacts 13, 14, and thence through the attack control circuit 43, 44, 45, to the positive terminal 15 of the source 16. Since the slat electrodes 4 are thus at a higher positive potential than the anodes 7 which are coated with secondary electron-emissive material, the slat electrodes act in the nature of dynatron grids or collectors to set up oscillations in the respective tuned circuits which are controlled by the organ keys 12. The key circuit through the common contact 14 also includes the primary winding 57 of an audio frequency output coupling transformer whose secondary winding 59 feeds the conductors 29, 30. For the purpose of controlling the harmonic content, the point 10 is coupled through condenser 33a to the respective harmonic control stops 37 and thence through the mixer 40 and the amplifier 31 to loudspeaker 32 in the manner described hereinabove.

While certain particular embodiments have been disclosed herein, it will be understood that various changes and modifications may be made therein without departing from the spirit and scope of the invention.

What is claimed is:

1. An electronic instrument, comprising, an electron tube having an electron-emitting cathode, a plurality of discrete electron tube sections surrounding said cathode, each section including in radial sequence an anode and a control grid and a slat electrode, an audio frequency oscillatory circuit connecting each grid to its associated anode, each oscillatory circuit being tuned to a different frequency, a keyboard having a series of keys one for each of said tube sections for controlling the regenerative feedback action of each section to cause a sustained audio frequency electric wave to be produced at the output of each section, an audio frequency transducer connected in common to all said sections and means connected in common to all the slat electrodes to selectively apply to said transducer any desired harmonics of the audio frequency wave.

2. An electronic organ, comprising, an electron tube having a central electron-emitting cathode, a plurality of discrete electron tube sections surrounding said cathode each including in radial sequence an anode and a control grid and a slat electrode, an audio frequency trans-

former for each section having a primary winding coupled for regenerative feedback action between the grid and anode, means to tune each transformer to a different audio frequency, an audio frequency amplifier and sound transducer combination, means to connect the secondaries of all said transformers in series to the input of said amplifier, a keyboard having a series of keys one for each tube section for controlling the regenerative action in each of said tube sections and means connected in common to all the slat electrodes to selectively apply to said transducer any desired harmonics of the audio frequency wave.

3. An electronic organ, comprising, an electron tube having a central electron-emitting cathode, a cage electrode immediately surrounding said cathode, said cage electrode having a series of conductive slat members defining therebetween electron windows, a plurality of control grids surrounding said cage and each located in registry with one of said windows, a plurality of anodes surrounding said control grids and also in registry with said windows, an audio frequency feedback circuit connecting each anode to each grid to generate discrete audio frequency oscillations, means to tune each feedback circuit to a different audio frequency, a source of common anode potential for all said anodes, a keyboard having a plurality of keys one for each of said feedback circuits for individually controlling the application of anode potential to any of said anodes and means connected in common to said slat members to selectively apply to said transducer any desired harmonics of the audio frequency wave.

4. An electronic organ, comprising, an electron tube having a central electron-emitting cathode, a conductive cage immediately surrounding said cathode and comprising a plurality of spaced conductive slats each pair of slats defining an electron permeable window, a plurality of grids surrounding said slats each in registry with one of said windows, a plurality of anodes surrounding said grids and also in registry with said windows, a tuned audio frequency feedback circuit connecting each grid to its anode, a keyboard having a plurality of keys for controlling each of said tuned feedback circuits, and circuit connections for deriving from said slat electrodes harmonics of the audio frequencies generated in said feedback circuits.

5. An electronic organ, comprising, an electron tube having a central electron-emitting cathode, a cage electrode immediately surrounding said cathode and having a plurality of slats defining electron permeable windows, said cage electrode having means to subdivide the space around said cathode into a series of discrete electron chambers with a window in each chamber facing said cathode, a separate control grid and anode located in each chamber, an audio frequency transformer having a primary winding connecting each grid to its associated anode for feedback action, a common source of direct current potential for all said anodes, a keyboard having an individual key for each anode for controlling the application of anode potential thereto, means to tune each transformer primary winding to a separate fundamental audio frequency, an audio frequency amplifier, means connecting all the secondary windings of said transformers in series across the input of said amplifier, a loudspeaker connected to the output of said amplifier, means connecting

said cage electrode through a load resistor to a source of direct current to derive across said resistor voltage waves which are harmonically related to said fundamental audio frequency waves, and means to mix said harmonic waves with said fundamental waves to produce at the output of said amplifier any desired harmonic content.

6. An electronic organ, comprising, an electron tube having a central electron-emitting cathode, 10 a slatted screen electrode immediately surrounding said cathode with each pair of adjacent slats defining an electron permeable window, a plurality of grids and anodes surrounding said cathode and respectively in registry with said windows, a plurality of tuned audio frequency feedback circuits one for each grid and anode, means to tune each feedback circuit to a different fundamental frequency, a common source of direct current potential for said anodes, 20 a keyboard having a separate key connecting said source to the electrical midpoint of each of said transformers, resistor means connecting the slats of said slatted electrode to said source, and means to select from said resistor voltage waves which are harmonically related to said fundamental frequencies.

7. An electronic organ according to claim 6, in which all of said slats are interconnected to form a single cage electrode, and said resistor means 30 comprises a single resistor for connecting said cage electrode to said source.

8. An electronic organ according to claim 6, in which each of said slats is individually connected through a separate resistor means to said source, and means are provided for selecting from each of said individual resistor means any desired harmonic of said fundamental frequency.

9. An electronic organ according to claim 6, in which the last-mentioned means includes an 40 additional series of stop switches for selectively connecting said resistor means to a common audio frequency amplifier.

10. An electronic organ according to claim 6, in which a common audio frequency amplifier is 45 provided for said audio frequencies and said harmonics, and the means for selecting said harmonics comprises a plurality of harmonic stop control keys for deriving from said resistor means corresponding harmonics of said fundamental frequencies, said stop control keys being connected through respective electrical filters to said amplifier.

11. An electronic organ according to claim 2, in which each of said feedback circuits is connected to a common source of tremolo potential 55 for imparting a tremolo effect to said fundamental frequency.

12. An electronic organ according to claim 3, in which said source of anode potential is connected through a time-constant circuit to 60 smooth the percussive effect of the generated audio frequencies.

13. An electronic organ comprising an evacuated envelope containing a central electron-emitting cathode, a plurality of separate anodes concentrically mounted around said cathode, a plurality of slat electrode elements concentrically mounted around the cathode and each located between the cathode and the respective 70 anode, a plurality of tuned oscillatory circuits each connected between said anode and cathode for generating sustained oscillations of respective fundamental audio frequencies, a keyboard having a plurality of keys one for each tuned 75 circuit, means connected in common to said slat

electrode elements to derive from said oscillations selected harmonics thereof, means to combine said oscillations with said harmonics, and a sound reproducer controlled by said oscillations and harmonics.

14. An electronic organ according to claim 13 in which said anodes have their surfaces facing the cathode provided with a coating of secondary electron-emissive material, each of said tuned circuits cooperating with an anode and a corresponding electrode element to generate said oscillations by dynatron action.
